UNITED STATES PATENT OFFICE.

EDWARD E. COLLINS, OF DETROIT, MICHIGAN.

WINDOW-CLEANER AND GLASS-POLISHER.

1,017,081.

Specification of Letters Patent. Patented Feb. 13, 1912.

Application filed March 2, 1908. Serial No. 418,719.

To all whom it may concern:

Be it known that I, EDWARD E. COLLINS, a citizen of the United States, residing at Detroit, in the county of Wayne, State of Michigan, have invented certain new and useful Improvements in Window-Cleaners and Glass-Polishers; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a window cleaning and glass polishing device, especially designed for removing paint or other foreign matter from window glass, and consists in the peculiar construction and association of parts hereinafter more fully set forth and claimed.

The object of the invention is to provide a simple and efficient device by means of which glass may be cleaned and polished, and paint and other matter readily removed from window glass by pressing the device forcibly against the surface of the glass to be cleaned and rubbing it thereover.

The above object is attained by the structure illustrated in the accompanying drawings, in which:—

Figure 1 is a plan view of the working face of my improved window cleaner and glass polisher. Fig. 2 is a transverse section therethrough as on line 2—2 of Fig. 1. Fig. 3 is an enlarged fragmentary view in plan showing more clearly the formation of the face of the device. Fig. 4 is a transverse section as on line 4—4 of Fig. 3. Fig. 5 is a transverse section as on line 5—5 of Fig. 3.

Referring to the characters of reference, 1 designates a plate of suitable metal and 45 of the required size, in the face of which are formed circular channels 2 producing between said channels annular beads or rings of gradually increasing diameter and concentric in relation. The central portion of 50 the plate has a depression 3 surrounded by a raised ring 4. Crossing the circular channels 2 and extending from the ring 4 to the margins of the plate 1 are the channels 5. These radial channels cut through the 55 circular concentric rings and divide them into segments 6 of varying sizes. These

segments as will be seen are quadrangular figures having four sharp edges and two parallel sides curved concentric with the circular channels 2.

Because of the shape of the segments 6 and of their relative position upon the plate, their sharp cutting edges are presented at various angles to any foreign substance upon the surface of the glass so that when the plate is pressed against the glass and reciprocated across its surface, the sharp edges of said segments execute a shearing and scraping operation which cuts and scrapes the foreign matter from the surface of the glass even though said foreign matter may be of the nature of paint or varnish. Because of the great number of the cutting segments upon the surface of the plate, any foreign matter upon the glass is acted upon many times during a single movement of the plate by the several segments which encounter it as the plate is moved across the surface of the glass, and as said segments stand at varying relations to one another, the angle of the cutting margins of the segments which successively engage said foreign matter is continually changing, thereby effecting a gradual reduction of said substance from all sides, as the plate is manipulated, whereby its removal from the surface of the glass is greatly facilitated.

In the application of this window cleaner and glass polisher, the best results are attained when water is used during the operation of cleaning the glass. The presence of the water causes the removed particles to flow into the channels between the segments and keeps the cutting edges of the segments free from adhering particles, preventing an accumulation of the removed matter upon the surface of said segments to such an extent as to hold them from proper contact with the surface of the glass. By a plentiful use of water the plate may be kept clean when in use.

For the purpose of manipulating the plate, it is provided on the back face thereof with a ring 7 which serves as a handle.

Having thus fully set forth my invention, what I claim as new and desire to secure by Letters Patent, is:—

As an article of manufacture, an integral structure for cleaning windows comprising a flat, metal plate provided with a plurality of radially disposed rows of sector blocks

rectangular in cross section projecting from the face of said plate, the blocks of each row being of gradually increasing length and all of said blocks having four cutting edges, there being in the central portion of said plate an unbroken ring having square cutting edges.

In testimony whereof, I sign this specification in the presence of two witnesses.

EDWARD E. COLLINS.
